US00D820795S

(12) **United States Design Patent** (10) Patent No.: **US D820,795 S**
(45) Date of Patent: ** *Jun. 19, 2018

(54) **KEYPAD**

(71) Applicant: **Lutron Electronics Co., Inc.**,
Coopersburg, PA (US)

(72) Inventors: **Alexander Wade Gage**, Havertown, PA
(US); **Elliot G. Jacoby**, Glenside, PA
(US); **Jason C. Killo**, Emmaus, PA
(US); **Brad Michael Kreschollek**,
Bethlehem, PA (US); **Noel Mayo**,
Philadelphia, PA (US); **Daniel Curtis
Raneri**, Bethlehem, PA (US)

(73) Assignee: **Lutron Electronics Co., Inc.**,
Coopersburg, PA (US)

(*) Notice: This patent is subject to a terminal disclaimer.

(**) Term: **15 Years**

(21) Appl. No.: **29/606,591**

(22) Filed: **Jun. 6, 2017**

(57) **CLAIM**

The ornamental design for a keypad, as shown and
described.

DESCRIPTION

FIG. 1 is a front perspective view of a keypad showing our
new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view of a second embodiment
thereof;

FIG. 8 is a front view thereof;

FIG. 9 is a left side view thereof;

FIG. 10 is a right side view thereof;

FIG. 11 is a top view thereof; and,

FIG. 12 is a bottom view thereof.

The dashed broken lines represent structure or features
which form no part of the claimed design; the broken lines
themselves form no part of the claimed design.

1 Claim, 8 Drawing Sheets
